ABSTRACT

One aspect of the invention is directed to shooting rests for supporting a firearm having a first portion and a second portion rearward of the first portion. In one embodiment, a shooting rest includes a frame, a front support for supporting the first portion of the firearm, a support member for carrying one or more weights, and a stop for inhibiting rearward movement of the firearm relative to the shooting rest. The front support is coupled to the frame, and the support member is positioned at least proximate to the frame. The stop includes a flexible portion and is also coupled to the frame.

SHOOTING RESTS FOR SUPPORTING FIREARMS

CROSS-REFERENCE TO RELATED APPLICATIONS

This application is a continuation-in-part of U.S. patent application Ser. No. 10/865,595, filed on Jun. 10, 2004, which claims priority to U.S. Provisional Patent Application No. 60/478,557, filed Jun. 13, 2003, both of which are incorporated by reference herein.

TECHNICAL FIELD

The present invention is directed to shooting rests for supporting firearms.

BACKGROUND

Firearm shooting sports are often associated with the sometimes painful recoil that may result from shooting firearms. Recoil from large caliber firearms can cause a shooter to flinch or jerk the firearm trigger in anticipation of the shock to the shooter's upper body. Flinching or jerking the trigger in anticipation of recoil is a common negative factor in a shooter's accuracy. Recoil can be described as the equal and opposite reaction to the momentum of an ammunition cartridge's projectile (e.g., bullet) and gunpowder charge upon firing of the cartridge. This momentum is imparted to the firearm, causing it to travel in the opposite direction of the fired bullet. The resulting recoil energy of the firearm can be calculated using the following equation derived from the Law of Conservation of Momentum:

$$\text{Recoil Energy (ft-lbs)} = \frac{(\text{Bullet Weight} \times \text{Bullet Velocity} + 4700 \times \text{Gunpowder Weight})^2}{64.348 \times \text{Firearm Weight}}$$

Where 4700 is the velocity of the gases generated by the burning gunpowder and 64.348 is a correction factor for the acceleration of gravity.

As can be seen by the above equation, increasing the Firearm Weight will result in a decreased Recoil Energy. As is common to the art of firearm manufacture, large caliber, heavy recoiling firearms are designed to be heavier in weight than small caliber, low recoiling firearms for precisely this reason. The additional weight has a dampening effect on the recoil felt by the shooter.

To test the accuracy of a firearm, a shooter will commonly shoot with the firearm placed atop a shooting rest, which in turn is placed on a bench. The shooter then fires the firearm from a sitting position behind the bench. This type of arrangement minimizes the shooting errors caused by the inability of the human body to hold a firearm perfectly steady and provides a steady, accurate method of supporting a firearm while shooting. Shooting from a bench has the drawback of subjecting the shooter to a higher degree of "effective recoil." Actual recoil energy of the firearm does not increase by shooting from a bench, but more of the recoil energy is transferred to the shooter in a sitting position than in a standing position. The standing position allows the entirety of the shooter's body to flex and partially absorb the recoil energy. In the sitting position, however, only the torso (i.e., shoulder to waist) of the shooter is available to flex and absorb the recoil. Because of the higher "effective recoil" when firing

2

from a sitting position, shooting a large caliber, heavy recoiling firearm from a bench can create an unpleasant experience when firing more than a few rounds. It is common for a shooter to fire upwards of twenty rounds when zeroing, or sighting-in, especially in the case of rifles and shotguns using telescopic sights.

BRIEF DESCRIPTION OF THE DRAWINGS

- 10 FIG. 1 is a perspective view of one embodiment of a recoil-reducing shooting rest with a rifle mounted in a firing position.
- 15 FIG. 2 is a side view of the shooting rest of FIG. 1.
- 15 FIG. 3 is a top view of the shooting rest of FIG. 1.
- 15 FIG. 4 is a detailed section view of a portion of the shooting rest taken along the plane including line 4-4 of FIG. 3.
- 15 FIG. 5 is a section view taken along the plane including line 5-5 of FIG. 3.
- 20 FIG. 6 is a front isometric view of a shooting rest in accordance with another embodiment of the invention.
- 20 FIG. 7 is a side elevation view of a shooting rest in accordance with another embodiment of the invention.
- 25 FIG. 8 is a side elevation view of a shooting rest in accordance with another embodiment of the invention.
- 25 FIG. 9 is a front isometric view of a shooting rest in accordance with another embodiment of the invention.
- 30 FIG. 10 is a front isometric view of a shooting rest in accordance with another embodiment of the invention.
- 30 FIG. 11 is a front isometric view of a shooting rest in accordance with another embodiment of the invention.

DETAILED DESCRIPTION

A. Overview

35 The following disclosure describes several embodiments of shooting rests for supporting firearms. One feature of several embodiments of the invention is that the shooting rests are expected to reduce the recoil energy experienced by a 40 shooter without modifying the firearm. For example, the shooting rests in these embodiments include a support member for carrying one or more weights, which reduce the recoil. Specifically, when the firearm is fired, the firearm and shooting rest can be considered as a single unit subjected to the 45 firearm's recoil energy. Mathematically, the weight of the shooting rest can be added to the weight of the firearm to yield a total Firearm Weight as used in the above-noted Recoil Energy equation. Because the total Firearm Weight is inversely proportional to recoil energy, adding more weight to 50 the shooting rest results in a corresponding reduction in recoil energy.

One aspect of the invention is directed to shooting rests for supporting a firearm having a first portion and a second portion rearward of the first portion. In one embodiment, a shooting rest includes a frame, a front support for supporting the first portion of the firearm, a support member for carrying one or more weights, and a stop for inhibiting rearward movement of the firearm relative to the shooting rest. The front support is coupled to the frame, and the support member is positioned at least proximate to the frame. The stop includes a flexible portion and is also coupled to the frame.

In another embodiment, a shooting rest includes a frame, a rear support coupled to the frame and positioned to carry the rear portion of the firearm, a front support movably coupled to the frame and positioned to carry the first portion of the firearm, a support member proximate to the frame, and an inhibiting member coupled to the frame and configured to

inhibit rearward movement of the firearm relative to the rear support. The front support is selectively movable in a direction generally parallel to an axis defined by the firearm. The support surface includes a surface for carrying a removable weight.

In another embodiment, a shooting rest includes a front support for supporting the first portion of the firearm, a rear support for supporting the second portion of the firearm, a support member for carrying a supplemental weight, and a stop for inhibiting rearward movement of the firearm relative to the shooting rest. The rear support is disconnected from the front support. The support member and the stop are coupled to the rear support.

Specific details of several embodiments of the invention are described below with reference to shooting rests for supporting firearms. Although several of the figures illustrate particular embodiments of shooting rests supporting rifles, those shooting rests can also be configured to support other types of firearms (e.g., shotguns). Several details describing well-known structures or processes often associated with shooting rests and firearms are not set forth in the following description for purposes of brevity and clarity. Also, several other embodiments of the invention can have different configurations, components, or procedures than those described in this section. A person of ordinary skill in the art, therefore, will accordingly understand that the invention may have other embodiments with additional elements, or the invention may have other embodiments without several of the elements shown and described below with reference to FIGS. 1-11. Where the context permits, singular or plural terms may also include the plural or singular term, respectively. Moreover, unless the word "or" is expressly limited to mean only a single item exclusive from other items in reference to a list of at least two items, then the use of "or" in such a list is to be interpreted as including (a) any single item in the list, (b) all of the items in the list, or (c) any combination of the items in the list. Additionally, the term "comprising" is used throughout to mean including at least the recited feature(s) such that any greater number of the same features and/or other types of features and components are not precluded.

B. Embodiments of Shooting Rests

FIGS. 1-3 illustrate one embodiment of a shooting rest 1 from varying angles with a firearm R (e.g., a rifle) placed atop the unit in the shooting position. The illustrated shooting rest 1 includes four main subsystems, namely, a rear support 2, a front support 3, a frame 4, and a support member or holder 5. The rear support 2 supports a buttstock 6 of the firearm R and the front support 3 supports the forend 7 of the firearm R. The frame 4 connects the rear support 2, front support 3, and holder 5 so that the shooting rest 1 is a single, rigid unit.

In one embodiment, the frame 4 is constructed of steel tubing and comprises a rear vertical section 13, a horizontal base section 14, a front vertical section 17, and a horizontal support member 24. The frame 4 provides a rigid infrastructure to the shooting rest 1 by joining all the subsystems in a single unit. The illustrated shooting rest 1 has three points of contact with a bench or other flat surface but in other embodiments the shooting rest may have more or less than three points of contact with the bench. In the illustrated embodiment, a rear foot 25 is located on the horizontal base section 14 of the frame 4, generally near the rear of the shooting rest 1 and two front feet 23 are located toward the outside edges of the holder 5. A three-point contact, or tripod arrangement, provides a stable and self-leveling configuration of the shooting rest 1. The front feet 23 and the rear foot 25 provide a

non-marring surface for contact of the shooting rest 1 with the bench and may also provide a large coefficient of friction between the shooting rest and the bench to minimize movement of the shooting rest during firearm discharge. The rear foot 25 can be threadably engaged to the horizontal base section 14. The threaded engagement allows for elevation adjustment for the rear portion of the shooting rest 1. The front feet 23 can be attached to the holder 5 by conventional fasteners (e.g., sheet metal screws not shown). In other embodiments, the frame 4 may have a different configuration.

The rear support 2 carries the buttstock 6 and provides the main transfer point of the recoil energy from the firearm R to the frame 4 of the shooting rest 1. In the illustrated embodiment, the rear support 2 includes of a buttstop 9, toe plate 10, and a recoil shoulder pad 16. As seen in FIG. 4, the rifle buttstock 6 rests atop the toe plate 10 with the rear surface of the buttstock, called a buttplate 12, contacting the inside surface 15 of the buttstop 9. In one embodiment, the buttstop 9 is formed from sheet metal and has two side panels and a rear panel that contacts the rear surface of the rifle buttstock 6. The buttstop 9 is rigidly connected to the toe plate 10, the rear vertical section 13 of the frame 4, and the horizontal support member 24 of the frame 4. In one embodiment, the buttstop 9 and toe plate 10 are fixed to the rear vertical section 13 and horizontal support member 24 of the frame 4 by threaded fasteners (e.g., bolts 35 in FIG. 4). Firing the firearm R will urge the firearm R to translate in a rearward direction, as indicated by arrow A in FIG. 2. With the buttplate 12 in contact with the inside surface 15 of the buttstop 9, the recoil energy of the firearm R will be transferred to the buttstop 9, and therefore to the entire shooting rest 1. Moreover, the buttstop 9 inhibits rearward movement of the firearm R relative to the shooting rest 1. The recoil pad 16 can comprise a resilient foam pad attached (e.g., sewn) to a thin nylon sleeve 36 that fits over the buttstop 9 to provide a soft, comfortable surface for the shooter's shoulder (FIG. 4). The nylon sleeve 36 covers the inside surface 15 of the buttstop 9 to provide a non-marring surface for contact with the buttplate 12 of the firearm R. The rear support 2 can have a different configuration in other embodiments.

Referring to FIGS. 1, 2, and 5, the illustrated front support 3 functions as a vertically adjustable (elevation adjustment) support for the firearm's forend 7. As shown in FIG. 5, a cylindrical, threaded ram 19 is removably inserted into an open end of the front vertical section 17 of the frame 4. A threaded adjustment wheel 20 rests atop the end of the front vertical section 17 of the frame 4 and is threadably engaged with the ram 19. Rotating the adjustment wheel 20 causes the ram 19 to translate vertically in relation to the front vertical section 17 of the frame 4. A cradle 21 is rigidly joined to the top surface of the ram 19. In one embodiment, the cradle 21 is a stamped sheet metal platform that supports a bag 22 filled with sand, or other particulate media, that is shaped to fit the typical contour of the firearm's forend 7. When the adjustment wheel 20 is rotated, the ram 19 moves vertically causing corresponding movement of the cradle 21 to adjust the vertical position of the rifle forend 7 to a desired position.

In one embodiment, the support member or holder 5 is formed of sheet metal and is rigidly connected to the horizontal base section 14 of the frame 4. Two holder support tubes 26 can be attached to horizontal section 14 to add support and stability to the holder 5 by preventing it from rotating about the horizontal section 14. In the illustrated embodiment, the holder 5 has a generally U-shaped cross-section with front and back lips 18 that curve upward from a bottom surface 27 of the holder 5. The holder 5 provides a stable platform to receive weights 8 placed on the shooting rest 1 by the shooter

and a structure for the attachment of the front feet 23 to the shooting rest 1. In other embodiments, the holder 5 may comprise other structures for supporting the weights 8 on the frame 4 or the weights may be attached directly to the frame 4. In the illustrated embodiment, the weights 8 are in the form of 25 lb. bags of lead shot due to their availability to a typical marksman and ease of portability. However, other forms of additional weight may be used. In the illustrated embodiment, the holder 5 is designed to hold up to four bags of lead shot 8, but only two bags are shown loaded on the holder. The lips 18 are sized to prevent the bags of lead shot 8 from shifting during discharge.

The subsystems of the shooting rest 1 may be joined via bolted or welded connections, for example, to form a rigidly constructed unit. In one embodiment, the shooting rest 1 can have a weight of approximately 15 lbs., an overall length of approximately 25 inches and a height of approximately 13 inches the shooting rest 1. Thus, the shooting rest 1 may be portable.

The recoil-reducing aspect of the shooting rest 1 is created by adding weight to the unit to increase resistance to the recoil of the firearm. Recoil energy is reduced when, according to the Law of Conservation of Momentum, the recoiling firearm encounters a greater opposing weight than merely the weight of the firearm alone. In the illustrated embodiment, the holder 5 supports this opposing weight (e.g., four 25 lb. bags of lead shot 8), so that the shooting rest 1 reduces recoil energy when the firearm R is discharged. According to the Law of Conservation of Momentum, written below in terms pertaining to the discussion, the Recoil Energy of the firearm can be calculated from the following equation:

$$\text{Recoil Energy (ft-lbs)} = \frac{(\text{Bullet Weight} \times \text{Bullet Velocity} + 4700 \times \text{Gunpowder Weight})^2}{64.348 \times \text{Firearm Weight}}$$

Where 4700 is the velocity of the gases generated by the burning gunpowder and 64.348 is a correction factor for the acceleration of gravity.

Increasing the Firearm Weight in the above-stated formula decreases the Recoil Energy. When the firearm is discharged, the firearm and the shooting rest 1 can be considered as a single unit subjected to the firearm's recoil. Mathematically, the weight of the shooting rest 1 can be added to the weight of the firearm R to yield a total Firearm Weight as used in the Recoil Energy equation. The more weight added to the rest 1, the higher the reduction in recoil. The illustrated holder 5 is designed to accept up to four 25 lb. bags of lead shot 8 but other types of weights could be used to increase the weight of the shooting rest 1. Twenty-five lb. bags of shot 8 are commonly available to the typical shooter and provide an easily portable system of weight addition for the shooting rest. In several applications, the recoil energy of a firearm can be reduced by up to 90% by adding weight to the shooting rest 1. The amount of weight needed to provide a certain percentage of recoil reduction is dependant on the caliber and size of the firearm used on the shooting rest 1.

In one embodiment of a method for operating the illustrated shooting rest 1, the shooter performs the following steps:

- 1) Place the shooting rest 1 on top of a relatively flat table or bench;
- 2) Place weights 8 on the holder 5 of the shooting rest 1;

- 3) Place the firearm R atop the shooting rest 1 in such a manner that the buttstock 6 of the firearm rests in the rear support 2 and the front support 3 cradles the forend 7 of the firearm;
- 4) Optionally adjust the vertical elevation of the front Support 3 and/or the rear foot 25 and/or make elevation sighting adjustments of the firearm R;
- 5) Sit behind the shooting rest 1 and firearm R with the rear support 2 of the shooting rest 1 close to the shooter. The shooting rest 1 may be oriented such that an imaginary line connecting the rear and front supports 2 and 3 is generally perpendicular to an imaginary line connecting the shooter's shoulders;
- 6) Place a shoulder against the shoulder rest 16 attached to the rear support 2;
- 7) Place both hands on the firearm R in a comfortable shooting position;
- 8) Pull the buttstock 6 of the firearm R towards the shoulder so as to make contact with the inside surface 15 of the rear support 2;
- 9) Fire or discharge the firearm R;
- 10) Discharge of the firearm R will cause the firearm to translate linearly, or recoil, in a rearward direction;
- 11) With the recoiling firearm R in firm contact with the rear support 2, the recoil energy of the firearm is transferred to the shooting rest 1;
- 12) The shooting rest 1 translates linearly, or recoils, in a rearward direction. Due to the resistance offered by the weights 8 added to the shooting rest, the shooting rest will recoil with a significantly reduced velocity and energy than the firearm alone; and
- 13) With the shooter in firm contact with the shooting rest 1 the shooter's upper body will in turn absorb the reduced recoil energy of the shooting rest.

With respect to the embodiment of the shooting rest 1 described above, various changes could be made in the above construction. For example, the frame 4 may comprise materials other than steel tubing. Also, the holder 5 may be an integral part of the frame 4 or the holder may be eliminated so that the weights 8 are supported directly on the frame. Further, the weights 8 could be separate components attached to the frame 4 or the weights may be integral with the frame so that the weight of the shooting rest 1 is increased and the recoil energy transferred to a shooter is decreased.

C. Additional Embodiments of Shooting Rests

FIG. 6 is a front isometric view of a shooting rest 100 in accordance with another embodiment of the invention. The shooting rest 100 is generally similar to the shooting rest 1 described above with reference to FIGS. 1-5. For example, the shooting rest 100 includes a rear support 2 for carrying the buttstock 6 of the firearm R, a front support 3 for carrying the forend 7 of the firearm R, and a frame 104 for connecting the rear and front supports 2 and 3. The illustrated frame 104, however, does not include a support member attached to the first horizontal section 14. Rather, the frame 104 includes two legs 114 (identified individually as 114a-b) projecting from the first horizontal section 14 and two front feet 23 attached to corresponding legs 114. The legs 114 and the front feet 23 provide stability to the shooting rest 100. In other embodiments, the rear and/or front support 2 and/or 3 can have a different configuration. For example, the rear and/or front support 2 and/or 3 can have a clamping mechanism that selectively grasps or clamps the firearm R to inhibit rearward movement of the firearm R during discharge. In one such embodiment, the clamping mechanism can include two

clamping members that selectively move toward each other and exert opposing forces on the firearm R to selectively secure the firearm R in a desired position for discharge.

The illustrated shooting rest 100 further includes a support member 105 attached to the second horizontal section 24 with a plurality of connectors 126. The illustrated support member 105 is a tray or plate having an upper surface 107 for supporting a plurality of removable weights 108. The weights 108 may rest on the surface 107 detached from the support member 105 or the weights 108 can be attached to the support member 105 with straps, Velcro®, or other fasteners. Although the illustrated support member 105 is a generally flat member, in other embodiments the support member may include one or more lips, recesses, protrusions, and/or other features for retaining the weights 108 on the support member 105 during discharge of the firearm R. For example, the support member 105 can be a tray, basket, or rack for carrying the removable weights 108. In additional embodiments, the support member 105 may not be positioned between the first and second horizontal sections 14 and 24, but rather the support member 105 can be positioned between the second horizontal section 24 and the firearm R. Alternatively, in other embodiments, the support member 105 can be attached to the first horizontal section 14 in lieu of the second horizontal section 24.

The connectors 126 couple the support member 105 to the second horizontal section 24. The illustrated connectors 126 are discrete and separate members that are attached to the second horizontal section 24 and the support member 105 with a plurality of fasteners 140 (e.g., screws, bolts, or pins). In other embodiments, the connectors 126 can be an integral part of the support member 105 or the frame 104. The connectors 126 can be flexible members or rigid members (e.g., sections of steel tubing). For example, the connectors 126 can include a strap, rope, cord, belt, and/or other suitable flexible member for coupling the support member 105 to the frame 104. In additional embodiments, the shooting rest 100 may not include the connectors 126. For example, the support member 105 may be a flexible member (e.g., a strap, rope, cord, or belt) configured to wrap around the second horizontal section 24 and support one or more weights. In one such embodiment, the weight may include a through hole through which the flexible support member is received to removably couple the weight to the frame.

FIG. 7 is a side elevational view of a shooting rest 200 in accordance with another embodiment of the invention. The shooting rest 200 is generally similar to the shooting rest 100 described above with reference FIG. 6. For example, the shooting rest 200 includes a front support 3 for carrying the forend 7 of the firearm R, a frame 204 for supporting the front support 3, and a support member 205 for carrying one or more removable weights (not shown). The illustrated frame 204 includes a front vertical section 17 attached to the front support 3 and a horizontal section 214 projecting from the front vertical section 17 opposite the front support 3. The illustrated support member 205 includes a horizontal portion 206a attached to the vertical section 17 of the frame 204 and a vertical portion 206b attached to the horizontal section 214 of the frame 204. The horizontal portion 206a has a plurality of recessed surfaces 207 for supporting removable weights during discharge. The contour of the individual recessed surfaces 207 can correspond to the contour of the weights, and the recessed surfaces 207 can be sized and configured to retain the weights during discharge. For example, the width of the horizontal portion 206a at the recessed surfaces 207 can be greater than the width of the horizontal portion 206a at other sections. In other embodiments, the support member 205 can

have a different configuration for carrying one or more removable weights. For example, the support member 205 can include a plurality of protrusions, bosses, hooks, wings, and/or other devices for interfacing with the weights.

5 The illustrated shooting rest 200 further includes a flexible member 250 for inhibiting rearward movement of the firearm R during discharge. The illustrated flexible member 250 includes a first portion 252a extending between the support member 205 and the buttstock 6 of the firearm R and a second portion 252b extending around the buttstock 6 in a direction generally transverse to the first portion 252a. The flexible member 250 can be a strap, cord, belt, or other flexible member that is selectively attached to the buttstock 6 of the firearm R. In other embodiments, the flexible member 250 can have a 10 different configuration. For example, the flexible member 250 can include a pocket into which at least a portion of the buttstock 6 of the firearm R can be received. In either case, the flexible member 250 inhibits rearward movement of the firearm R during discharge. Although the illustrated shooting rest 15 20 200 does not include a rear support for carrying the buttstock 6 of the firearm R, in other embodiments the shooting rest may include a rear support.

FIG. 8 is a side elevational view of a shooting rest 300 in accordance with another embodiment of the invention. The 25 illustrated shooting rest 300 includes a rear portion 301a and a front portion 301b spaced apart and disconnected from the rear portion 301a. The rear portion 301a includes a rear support 2 for carrying the buttstock 6 of the firearm R, a first frame 304a for supporting the rear support 2, and a support member 305 for carrying one or more removable weights. The first frame 304a includes a vertical section 313 attached to the rear support 2 and a horizontal section 314 projecting from the vertical section 313 opposite the rear support 2. The support member 305 is attached to the horizontal section 314 30 and positioned so that a shooter can place one or more weights on the support member 305. The support member 305 can be a tray, plate, basket, or other suitable member for carrying the weights. The illustrated support member 305 is a plate having upward extending ends 318 to prevent the weights from falling off the support member 305 during discharge. The rear portion 301a may further include one or more front feet 23 attached to the support member 305 and a rear foot 25 attached to the first frame 304a for increasing stability.

The front portion 301b of the shooting rest 300 includes a 45 front support 3 for carrying the forend 7 of the firearm R and a second frame 304b for supporting the front support 3. The second frame 304b includes a plurality of legs 360 for providing stability to the front portion 301b. In additional embodiments, the front support 3 can include a clamping device to inhibit rearward movement of the firearm R during discharge, and/or the front portion 301b may include the support member 305. In other embodiments, the shooting rest 300 may not include the rear or front portion 301a or 301b.

FIG. 9 is a front isometric view of a shooting rest 400 in 55 accordance with another embodiment of the invention. The illustrated shooting rest 400 is generally similar to the shooting rest 100 described above with reference to FIG. 6. For example, the illustrated shooting rest 400 includes a rear support 402 for carrying a rear portion of a firearm, a front support 403 for carrying a forward portion of the firearm, a frame 404 extending between the rear and front supports 402 and 403, and a support member 405 for carrying one or more removable weights. The illustrated frame 404 includes a rear vertical section 413 attached to the rear support 402, a lower horizontal section 414 projecting from the rear vertical section 413, a front vertical section 417 projecting from the lower horizontal section 414, and first and second upper horizontal 60 65 sections 418 and 419.

sections **424a-b** extending between the front vertical section **417** and the rear vertical section **413**. In the illustrated embodiment, the rear vertical section **413**, the lower horizontal portion **414**, the front vertical section **417** are integral sections of a single member, and the first and second upper horizontal sections **424a-b** are separate members attached to the rear and front vertical sections **413** and **417**. In other embodiments, however, the frame **404** can have a different configuration.

The illustrated rear support **402** includes a horizontal wall **450**, two side walls **452** projecting upward from the horizontal wall **450**, and a vertical wall **454** projecting upward from the horizontal wall **450** and extending between the two side walls **452**. The horizontal, side, and vertical walls **450**, **452**, and **454** define a pocket sized to receive an aft portion of a firearm. The horizontal, side, and/or vertical wall **450**, **452**, and/or **454** can be rigid panels. As such, the horizontal wall **450** is positioned to support the weight of the aft portion of the firearm; the side walls **452** are positioned to prevent the aft portion of the firearm from sliding off the horizontal wall **450**; and the vertical wall **454** is positioned to inhibit rearward movement of the firearm during discharge. In the illustrated embodiment, the rear support **402** further includes a sleeve **455** placed over the horizontal, side, and vertical walls **450**, **452**, and **454**. In other embodiments, the rear support **402** can have a different configuration.

The illustrated front support **403** includes a base **470**, a cradle **421** carried by the base **470**, and a bag **422** carried by the cradle **421**. The illustrated base **470** includes a plate **472** and a securing member **474** attached to the plate **472**. The plate **472** is positioned over the first and second upper horizontal sections **424a-b**. The securing member **474** includes a first portion **475a** positioned under the first and second upper horizontal sections **424a-b** and end portions **475b** projecting from the first portion **475a** toward the plate **472**. The plate **472** and the securing member **474** connect the front support **403** to the first and second upper horizontal sections **424a-b** such that the front support **403** can slide along the upper horizontal sections **424** in a direction **D₁**. As a result, the distance between the front support **403** and the rear support **402** can be changed to accommodate firearms with different lengths and/or configurations. In additional embodiments, the front support **403** may not be slidably coupled to the first and second upper horizontal sections **424a-b**.

The base **470** may also include a first locking mechanism **478** (only a portion of which is shown in FIG. 9) for selectively inhibiting movement of the base **470** along the first and second upper horizontal sections **424a-b** in the direction **D₁**. The first locking mechanism **478** may include a stop or other device for contacting the first and/or second upper horizontal sections **424a-b** to inhibit relative movement between the base **470** and the upper horizontal sections **424**. The illustrated first locking mechanism includes a handle **480** configured such that a shooter can pivot the handle (a) downward to selectively lock the base **470** in a specific position, and (b) upward to enable the base **470** to move in the direction **D₁**.

The illustrated base **470** further includes a height adjustment mechanism **482** for adjusting the elevation of the cradle **421** and the vertical aim of the firearm. The height adjustment mechanism **482** includes a handle **484** and a hub **485** with a threaded hole (not shown) operably coupled to the handle **484**. The threaded hole is positioned to interact with a threaded shaft (not shown) of the cradle **421**. As such, a shooter can rotate the handle **484** to pivot the hub **485** about an axis A-A, which drives the threaded shaft and cradle **421** upward or downward along the axis A-A. The base **470** may also include a second locking mechanism (only a portion of

which is shown in FIG. 9) for inhibiting vertical movement of the cradle **421** along the axis A-A. The illustrated second locking mechanism includes a handle **486** for enabling a shooter to lock the cradle **421** in a specific position at a particular elevation. In other embodiments, the cradle **421** may not be movable along the axis A-A.

The illustrated cradle **421** includes a first portion **488** attached to the base **470**, a second portion **490** moveably attached to the first portion **488**, and a driving mechanism (only a portion of which is shown in FIG. 9) attached to the first and second portions **488** and **490** for moving the second portion **490** relative to the first portion **488**. The driving mechanism includes a handle **492** that allows a shooter to move the second portion **490** laterally in a direction **D₂** relative to the first portion **488**. The driving mechanism accordingly enables a shooter to adjust the position of the second portion **490** and the horizontal aim of the firearm.

The support member **405** in the illustrated embodiment is attached to the lower horizontal section **414** of the frame **404** and configured to carry at least one removable weight. Although the support member **405** is attached to the lower horizontal section **414** proximate to the forward vertical section **417**, in other embodiments the support member **405** can be attached to an aft portion of the frame **404**. The illustrated support member **405** is a tray having front and rear lips **418a-b** for preventing the weights from falling off the support member **405** during discharge. The support member **405** may further include a raised portion **407** extending laterally across the support member **405** in a direction generally parallel to the front and rear lips **418a-b**. The raised portion **407** inhibits the weights from moving on the support member **405** during recoil. In additional embodiments, the support member **405** can have a different configuration. For example, the support member can be a reservoir configured to receive water, sand, lead shot, pellet-like material, and/or other material for adding weight to the shooting rest. In other embodiments, portions of the frame **404** can function as the support member. For example, the frame may include an opening configured to receive water, sand, lead shot, pellet-like material, and/or other material for adding weight to the shooting rest.

The illustrated shooting rest **400** further includes an angle adjustment mechanism **460** attached to the frame **404** and a rear foot **425** attached to the angle adjustment mechanism **460**. The angle adjustment mechanism **460** can include a threaded hole; and the rear foot **425** can include a threaded shaft that projects through a hole in the lower horizontal section **414** and is received in the threaded hole of the angle adjustment mechanism **460**. As a result, a shooter can pivot the angle adjustment mechanism **460** about an axis B-B to drive the rear foot **425** upward or downward in a direction **D₃** to adjust the elevation of the frame **404** and the vertical aim of the firearm. In other embodiments, the shooting rest **400** may not include the angle adjustment mechanism **460** and/or the rear foot **425**.

FIG. 10 is a front isometric view of a shooting rest **500** in accordance with another embodiment of the invention. The illustrated shooting rest **500** is generally similar to the shooting rest **400** described above with reference to FIG. 9. For example, the shooting rest **500** includes a rear support **402**, a front support **403**, a frame **404** connecting the rear and front supports **402** and **403**, and a support member **505** attached to the frame **404**. The illustrated support member **505**, however, projects from the lower horizontal section **414** of the frame **404** in a direction generally parallel to the axis A-A. The support member **505** can be an integral part of the frame **404** or a separate component attached to the frame **404**. The support member **505** is configured to be received within an aper-

11

ture of a removable weight W (shown in broken lines) to secure the weight W to the frame 404. In other embodiments, the support member 505 may interact with and/or engage a removable weight having a different configuration such that the support member 505 releasably secures the weight W to the frame 404. In additional embodiments, the shooting rest 500 may include multiple support members 505 projecting from the lower horizontal section 414 and/or other portions of the frame 404. For example, in one such embodiment, the support members can project from the legs 114a-b of the frame 414 or the legs 114a-b can include a section for receiving the weights W.

FIG. 11 is a front isometric view of a shooting rest 600 in accordance with another embodiment of the invention. The illustrated shooting rest 600 is generally similar to the shooting rest 400 described above with reference to FIG. 9. For example, the shooting rest 600 includes a rear support 602, a front support 403, a frame 404 connecting the rear and front supports 602 and 403, and a support member 405 attached to the frame 404. The illustrated rear support 602, however, includes a plate 650 attached to the frame 404, a bag 652 attached to the plate 650, and a strap 656 attached to the plate 650, bag 652, and/or frame 404. The bag 652 can be generally similar to the bag 422 of the front support 403. For example, the bag 652 can have a support surface 654 with a V-shape configuration for supporting the buttstock of a firearm. The strap 656 is configured to wrap around the buttstock of the firearm and inhibit rearward motion of the firearm during discharge. The illustrated strap 656 includes two end portions 658a-b attached to the plate 650, bag 652, and/or frame 404 and an intermediate section 659 between the end portions 658a-b. The intermediate portion 659 is positioned to contact the butt of the firearm. In other embodiments, the shooting rest 600 may include multiple straps that extend between the frame 404 and the firearm to inhibit movement of the firearm during discharge. For example, the shooting rest 600 may include one or more straps coupled to the swivel stud, scope base, and/or firearm wrist.

From the foregoing, it will be appreciated that specific embodiments of the invention have been described herein for purposes of illustration, but that various modifications may be made without deviating from the spirit and scope of the invention. For example, many of the elements of one embodiment can be combined with other embodiments in addition to or in lieu of the elements of the other embodiments. Accordingly, the invention is not limited except as by the appended claims.

We claim:

1. A shooting rest for supporting a firearm having a first portion and a second portion rearward of the first portion, the shooting rest comprising:
  - a frame;
  - a front support for supporting the first portion of the firearm, the front support being coupled to the frame;
  - a rear support for supporting the second portion of the firearm, the rear support including a stop configured to inhibit rearward movement of the firearm relative to the shooting rest, the stop being rigidly coupled to the frame;
  - the front and rear supports defining a holding axis therebetween along which the firearm extends when supported by the front and rear supports; and
  - a support member configured for carrying at least one weight for reducing recoil felt by a shooter, the support member being configured to prevent the at least one weight from moving in a longitudinal direction between the front support and the rear support during firearm discharge, the support member being positioned at least

12

partially behind the front support and at least partially in front of the rear support, and the support member including first and second portions on opposite sides of the holding axis, wherein the frame, the rear support and the support member are coupled together in a fixed, non-slidable configuration.

2. The shooting rest of claim 1 wherein: the frame comprises an upper horizontal section and a lower horizontal section.
3. The shooting rest of claim 1 wherein the stop further comprises a pocket sized to receive a butt of the firearm.
4. The shooting rest of claim 1 wherein the support member comprises a projection projecting from the frame.
5. The shooting rest of claim 1 wherein the support member comprises a section of the frame configured to removably carry the at least one weight.
6. The shooting rest of claim 1 wherein the support member comprises a flexible strap.
7. The shooting rest of claim 1 wherein the stop comprises a rigid rear panel rigidly coupled to the frame and two side panels coupled to the rigid rear panel, the side panels and rear panel forming a pocket sized to receive a butt of the firearm.
8. The shooting rest of claim 7 further comprising a cover configured for covering inner and outer surfaces of the side and rear panels.
9. The shooting rest of claim 7 further comprising a cover including panel receiving compartments sized for receiving the side and rear panels.
10. The shooting rest of claim 7 further comprising a cover including side portions receivable over respective side panels, a rear portion receivable over the rear panel, and a lower portion extending between the side portions in front of the rear portion for reception of a bottom of the butt of the firearm when the butt is received in the pocket.
11. The shooting rest of claim 1 wherein the support member includes at least one fastener configured for releasable fastening engagement with said at least one weight for preventing the at least one weight from moving in a longitudinal direction between the front support and the rear support during firearm discharge.
12. The shooting rest of claim 11 wherein the support member includes a plurality of fasteners configured for releasable fastening engagement with the at least one weight.
13. The shooting rest of claim 11 wherein the fastener is configured for mating engagement with said at least one weight.
14. The shooting rest of claim 13 wherein the fastener includes a mating member sized and shaped for reception in an opening of said at least one weight.
15. The shooting rest of claim 14 wherein the mating member projects in an upward direction for reception of the at least one weight over the mating member.
16. The shooting rest of claim 1 wherein the support member includes a support surface sized and shaped for carrying at least one weight weighing at least 25 pounds.
17. The shooting rest of claim 1 wherein the support member comprises a tray including a support surface sized and shaped for carrying the at least one weight.
18. The shooting rest of claim 1 wherein the first and second portions of the support member have widths on opposite sides of the holding axis extending transversely with respect to the holding axis, the widths extending outwardly to respective outer ends of the support member each positioned outboard of the rear support with respect to the holding axis.
19. The shooting rest of claim 1 wherein the support member comprises a support surface and a portion protruding

upward and positioned to retain the at least one weight on the support member during firearm discharge.

20. The shooting rest of claim 19 wherein the portion protruding upward is positioned for preventing the at least one weight from moving forward during firearm discharge. 5

21. The shooting rest of claim 1 wherein the support member is sized and shaped to underlie an entirety of the at least one weight.

22. The shooting rest of claim 1 wherein the support member and stop have widths extending transversely with respect 10 to the holding axis and the support member is wider than the stop.

23. The shooting rest of claim 1 wherein the first and second portions of the support member on opposite sides of 15 the holding axis are connected to each other.

24. The shooting rest of claim 1 wherein the support member includes two holders each configured for carrying at least one weight.

25. The shooting rest of claim 1 wherein the stop comprises a flexible strap configured to contact the rear portion of the 20 firearm for inhibiting rearward movement of the firearm during firearm discharge.

26. The shooting rest of claim 1 wherein the support member includes a support surface sized and shaped for carrying the at least one weight, the support surface being positioned at 25 least partially between the front and rear supports.
